Theodore W. Gillagore, of Philadelphia, Pa.

Assignor to Savery Co., of same place.

Letters Patent No. 1220, dated April 3, 1860.

The schedule referred to in these Letters Patent and making part of the same.

To all whom it may concern:

Be it known that I, Theodore W. Gillagore, of the City of Philadelphia, in the State of Pennsylvania, have invented or produced a new and original Design for Fire Dogs, and I do hereby declare that the following is a full, clear and exact description of the same, reference being had to the annexed drawing, making a part of this Specification, and to the letters of reference marked thereon.

The said design I call the "Eagle Pattern." It consists of a combination of ornamentations representing carvings in the forms of scrolls, crescents, an angular center, and shields, surmounted by an eagle - the whole being arranged together, as hereinafter described, to be cast in metal to serve as the front part of a fire dog.

In the drawing A.A. represent the scrolls, B.B. the crescents, C. the angular center, D.D. the shields, and E. the eagle.

The leg scrolls A.A. turn inwards and embrace the crescents, B.B.; the scroll A' turns upward, rests directly upon the scrolls, A.A., and immediately supports the ornamented shield D', crescent B', and scroll A'. A' the said scroll A' being connected with the scrolls A.A. by means of the crescents B.B. the said

Des. 1220

marked shield D' and the crescents B² B⁴. The crescents B² B⁴ rest upon the scrolls A² A⁴ and immediately support the union shield D. The eagle E. surmounts the whole, grasping the union shield - all being arranged so as to produce the external and internal contours shown in the drawing, as one piece.

What I claim as my invention or production, and desire to see
cure by letters patent is -

The Eagle-pattern Design, for Fire Dogs, described and set
forth
